UNITED STATES PATENT OFFICE

132,029

DESIGN FOR A FLAG

Charles Raymond Johnson, Pittsburgh, Pa., assignor to Gardner Displays Company, a corporation of Pennsylvania

Application January 28, 1942, Serial No. 105,470

Term of patent 7 years

To all whom it may concern:

Be it known that I, Charles Raymond Johnson, residing at Pittsburgh, in the county of Allegheny and State of Pennsylvania, have invented a new, original, and ornamental Design for Flags, of which the following is a specification, reference being had to the accompanying drawing, forming part thereof.

The figure is a plan view of a flag, showing my new design.

I claim:

The ornamental design for a flag, as shown.

CHARLES RAYMOND JOHNSON.
